UNITED STATES PATENT OFFICE.

JOHN NORDGRAN, OF SALT LAKE CITY, UTAH.

DESIGN FOR AN AUTOMOBILE SIGNAL CASING.

Application filed January 18, 1926. Serial No. 16,152. Term of patent 14 years.

To all whom it may concern:

Be it known that I, JOHN NORDGRAN, a citizen of the United States, residing at Salt Lake City, in the county of Salt Lake and State of Utah, have invented a new, original, and ornamental Design for Automobile Signal Casing, of which the following is a specification, reference being had to the accompanying drawings, forming a part thereof.

In the accompanying drawings Fig. 1 is a front elevation of an automobile signal casing showing my new design, and Fig. 2 is an end elevation thereof.

I claim:

The ornamental design for an automobile signal casing, substantially as shown.

JOHN NORDGRAN.
